[57] CLAIM

The ornamental design for an automobile headlight lens, substantially as shown and described.

DESCRIPTION

FIG. 1 is a front perspective view of an automobile headlight lens showing my new design;

FIG. 2 is a rear view thereof on an enlarged scale;

FIG. 3 is a top view thereof on an enlarged scale;

FIG. 4 is a side view thereof on an enlarged scale;

FIG. 5 is a cross-sectional view taken along line 5—5 of FIG. 2;

FIG. 6 is a front perspective view of modified form of the lens;

FIG. 7 is a rear view thereof on an enlarged scale;

FIG. 8 is a top view thereof on an enlarged scale;

FIG. 9 is a side view thereof on an enlarged scale; and

FIG. 10 is a cross-sectional view taken along line 10—10 of FIG. 7.
